Primary Examiner — Barbara Fox*Assistant Examiner* — Lilyana Bekic(74) *Attorney, Agent, or Firm* — Melanie G. Gover(57) **CLAIM**

The ornamental design for a respirator mask face seal, as shown and described.

DESCRIPTION

The subject matter disclosed herein is related to subject matter disclosed in PCT Patent Application No. PCT/US14/50847, which is incorporated herein by reference in its entirety.

FIG. 1 is a left front perspective view of a respirator mask face seal showing the design, the face seal shown attached to a respirator mask;

FIG. 2 is a front plan view thereof;

FIG. 3 is a front view of the respirator mask;

FIG. 4 is a top plan view of FIG. 1;

FIG. 5 is a bottom plan view thereof; and,

FIG. 6 is a left side view thereof, the right side being a mirror image of this view.

The broken line showing of the respirator mask illustrates the environment of the respirator mask face seal and forms no part of the claimed design.
